(57) **CLAIM**

The ornamental design for a flowerpot, as shown and described.

DESCRIPTION

FIG. 1 is a top view of a flowerpot showing my new design. FIG. 2 is a top, rear and left side perspective view thereof; FIG. 3 is top, front and right side perspective view thereof; FIG. 4 is a side view thereof, an opposite side view being identical;

FIG. 5 is a front view thereof, a rear view being identical; and,

FIG. 6 is a bottom view thereof.

The broken lines of FIG. 6 illustrate portions of the flowerpot that form no part of the claimed design.
